UNITED STATES PATENT OFFICE.

CHARLES B. STERLING, OF NEW YORK, N. Y.

SIGNALING SYSTEM.

SPECIFICATION forming part of Letters Patent No. 593,314, dated November 9, 1897.

Application filed February 25, 1897. Serial No. 624,935. (No model.)

To all whom it may concern:

Be it known that I, CHARLES B. STERLING, a citizen of the United States, residing at New York city, in the county and State of New York, have invented certain new and useful Improvements in Signaling Systems, of which the following is a full and accurate description, reference being had to the accompanying drawings, forming part of this specification.

The object of my invention is to so connect a plurality of electromagnets for sounding alarms at a number of points distant from each other—as in the various rooms of a hotel or widely-separated points of a railway system, &c.—with each other and with the generator that a single circuit maker and breaker operated by one of said magnets shall serve to automatically make and break the circuits through all of said magnets, to cause all of the alarms to be sounded a number of times upon the closing of a circuit by hand, and also to provide the system with a number of widely-scattered circuit-closers the operation of any of which will close the circuits through one or all of the magnets in the system and through the aforesaid circuit maker and breaker.

In all embodiments of my invention it is essential that there shall be an electromagnet, of any suitable form, which automatically controls a circuit making and breaking device for making and breaking the circuit through all of the electromagnets in the system.

In the accompanying drawings, Figure 1 shows my invention embodied in a car alarm system. Fig. 2 shows the invention embodied in a system for starting cars. Fig. 3 shows a fire-alarm installation for factories.

40 A is a solenoid.

B is the vertically-movable core.

C is a spring-operated catch carried by the lower end of the core.

D is a wheel having pins upon one of its faces and teeth upon its periphery.

E is the weighted lever for controlling the timing of the strokes of the core.

F indicates the spring for holding the circuit maker and breaker in its upper position.

G is the rod for carrying the maker and breaker.

I and J are the contacts, which are bridged by H.

For a complete and detailed description of the construction and operation of the parts just above enumerated I refer to United States Letters Patent No. 552,933, dated January 14, 1896, and granted to my assignees.

Referring to Fig. 1, the trolley is connected by conductors M and N with the coil, which is in turn connected by conductors O and L with the contact J. The opposite contact I is connected by a conductor K with the conductors P and Q, the former of which leads to the right-hand bell. Preferably the magnet A will be placed in the car underneath a seat or at any other position where it will be protected from rain, snow, dust, &c. The alarms under the platforms may consist of coils R R', inside of the bells S S'. If the right-hand bell is to be sounded, the motorman will put his foot upon the pin X, operating the lever W and throwing the bridging-contact Y into engagement with the contacts U U. The current will then flow through M N, coil A, conductors O L, contact J, bridge H, contact I, conductors S, K, and P, coil R of bell, conductor T, contacts U U, bridge Y, and conductor V to the rail. It is unnecessary for the motorman to repeatedly strike the treadle. He merely holds it in depressed position. The core B is suddenly drawn up into the coil A to the full limit of its upward stroke, the latch C slipping past the pins on wheel D. Near the end of its upward stroke the core (into which the rod G loosely fits, as explained in my former patent) lifts the rod G and moves the bridge H out of engagement, as shown, with the contacts I and J, the springs F holding the circuit maker and breaker in elevated position. The circuit having been broken at I and J, the core is released, and in falling has to overcome the retarding effect of the wheel D and spring F. The spring-latch on its downward movement strikes a pin on the wheel D and is held stationary until the weighted lever E is operated. Then the weight of the falling core drives

the circuit maker and breaker out of engagement with the springs F, and the bridge H will engage the contacts I and J, whereupon the operations will be repeated, and as long as the lever W is depressed. If the left-hand alarm is to be sounded, the treadle X' is depressed.

By the use of the magnet A and its circuit maker and breaker I assure the intermittent sounding of either alarm by merely depressing the corresponding platform-lever. Any other suitable form of magnet or circuit-maker may be used, if desired; also, any other form of magnet for the platform-alarms. The mechanism for timing the strokes may also be quite different from that herein described.

I desire it to be understood that the foregoing statements as to variations in structure also apply to all embodiments of my invention.

In Fig. 2 I show one embodiment of my invention which may be used for starting trains from different sections of a railway depot or yard. S are the gongs placed at the different sections. One of said gongs is shown in inverted position to illustrate the relations of coil, core, and gong. A' and B' are electric-lighting wires. C' and D' are branches thereof from to the fuse-block E'. F' is a switch. G' is the conductor which leads from the switch directly to the wire H. Short conductors I' connect H with all the bells, and conductors J' connect the bells with contacts K'. Switches L', corresponding in number to contacts K', are pivoted to the metallic bar M'. Conductor Z connects said bar with the wire K, leading to the circuit maker and breaker. The switch F' being closed the current flows from A' over D', wires M and N, coil A, wires O and K, contacts I and J, and bridge H, and wires L, P, and C' to B'. This causes an intermittent operation of the circuit maker and breaker. If the operator wishes to sound any one of the gongs, he operates the switch L' which corresponds to that gong. The current is then branched over wires G' H' and the wires I' leading to said gong, then by wire J', contact K', switch L', bar M', and wire Z to the circuit maker and breaker. He counts the strokes of the circuit maker and breaker, and thus learns the number of sounds given by the alarm thrown into circuit. The switches L' may be operated in any order desired. If preferred, the switch F' may be kept open normally, being closed only when a switch L' is to be operated.

In order that they may be protected from mishandling, &c., the magnet A, circuit-maker, wheel D, &c., may be put into a case, as indicated.

In Fig. 3 I have shown a fire-alarm system which embodies my invention. Two gongs S are placed on the floors of the building, (four floors are shown in Fig. 3,) and there are

three push-buttons D² on each floor. When a fire is discovered, a workman pushes any one of the buttons D² and a battery-circuit is closed. This circuit is over wire D³, wire D⁵, wire D⁷, wire D⁹, wire E², battery E³, wire E⁴, binding-post H⁵, wire E⁶, through coil of magnet E⁷, wire D¹⁰, wire D⁸, wire D⁶, and wire D⁴. The magnet E⁷ attracts its armature F², which is held away from the magnet by a spring F³. The free end of the armature carries a bridging-contact F⁴, which closes the alarm-circuits across the two contacts B³. The current then flows from the lighting-wire B', over wire B², over contacts B³ and bridge F⁴, over wires P and L, contact J, circuit maker and breaker H, contact I, and wire J. There the current divides, part flowing directly over wire O, coil A, wire N, and wire M to lighting-wire A'. The rest of the current flows over wire P Z, over wire C², over wire C⁶, wire C⁸, through the coils of the bells S, wires C⁴, and wires C⁵ to wire A'. Thus all the bells are thrown into circuit by the simple pressure of a push-button at any point in the factory.

In order that the bells may continue to be sounded after the workman has released the push-button and as long as desired, I provide a latch G², which is pulled by a latch G³ into a position underneath the free end of the armature F², holding it permanently in its elevated and circuit-closing position. An electromagnet G⁴ is provided for restoring the latch G² to its normal position, breaking the signaling-circuits at the bridge F⁴. This magnet G⁴ is included in a battery-circuit closed by a push-button H². The current flows over wire H³, wire H⁴, through coil G⁴, wire H⁵, binding-post E⁶, wire E⁴, battery E³, wire E², and wire H³.

The magnets A, E⁷, and G⁴ are preferably placed within a casing, as indicated.

Instead of push-buttons D² on the floors, fusible or other thermostatic circuit-closers may be substituted.

My invention may be embodied in other forms than those herein described.

I do not of course wish to be understood as confining myself to the details herein shown, which may be departed from and still be my invention.

What I claim is—

1. In a signaling system, supply-conductors, a circuit-closer an electromagnet and an automatically-operating circuit maker and breaker controlled by said magnet, all included in the supply-circuit, and a branch circuit including said circuit maker and breaker and a plurality of alarms, in combination with means for moving the circuit-closer into position, a lock or latch for holding it in said position, and means for freeing the same, substantially as and for the purpose described.

2. In a signaling system, supply-conduc-

tors, a circuit-closer, an electromagnet and an automatically-operating circuit maker and breaker controlled by said magnet, all included in the supply-circuit, and a branch

5 circuit including said circuit maker and breaker and a plurality of alarms, in combination with an electromagnet for moving the circuit-closer into position, a lock or latch for holding it in said position, one or more circuit-closers for closing a circuit through the

electromagnet, and means for moving the lock or latch to release the first-named circuit-closer, substantially as and for the purpose described.

In witness whereof I have hereunto signed 15
my name this 20th day of February, 1897.

CHARLES B. STERLING.

In presence of—

JNO. P. DAVISON,

W. H. BERRIGAN, Jr.
